UNITED STATES PATENT OFFICE.

JOSEF HEROLD, OF BRÜNN, AND CARL HEROLD, OF KÖNIGSFELD, AUSTRIA-HUNGARY, ASSIGNORS TO RUNDWEBSTUHL FABRIK HEROLD & RICHTARDS, OF BRÜNN, AUSTRIA-HUNGARY.

CIRCULAR LOOM.

SPECIFICATION forming part of Letters Patent No. 629,251, dated July 18, 1899.

Application filed February 11, 1898. Serial No. 669,898. (No model.)

To all whom it may concern:

Be it known that we, JOSEF HEROLD, manufacturer, of 23 Zollhausglacis, Brünn, and CARL HEROLD, manufacturer, of Königsfeld, 5 Moravia, Austria-Hungary, have invented certain new and useful Improvements in Circular Looms; and we do hereby declare that the following is a full, clear, and exact description of the same.

10 Reference is made to the accompanying drawings, in which—

Figure 1 is a side elevation, partly in vertical section; Fig. 1^a, a detail in section. Fig. 1^b is a detail end elevation of certain gears; Fig. 2, a vertical section of a part of the loom, drawn to a larger scale; Fig. 3, a plan of the electromagnetic driving mechanism, together with the shuttle and shuttle-guard and the device for beating up the weft, the 20 upper ring *f* being omitted; Fig. 4, a detail elevation of the shuttle; Fig. 5, a diagram of the circuits for energizing the magnets and throwing out of gear the weft-guard and shuttle-guard. Fig. 6 shows the ring *h*, with the 25 spiral spring wound thereon. Fig. 7 is a plan view of a portion of the heddles and the heddle-leaves. Fig. 7^a is a sectional view on the line *y* *y* of Fig. 7. Fig. 8 is a detail cross-section showing the shuttle and the weft-guard.

30 The invention relates to improvements in circular or rotary looms.

The present improvements relate more particularly to, first, a novel electromagnetic driving arrangement for the shuttle; second, 35 a new weft-guard for rotary looms; third, a shuttle-guard for rotary looms; fourth, a new construction of the arrangement for beating up the weft-threads to the finished portion of the cloth; fifth, a new arrangement of the 40 leaves of heddles; sixth, an arrangement for folding the completed tubular-shaped goods.

The construction of our circular or rotary loom has already been made known in our Patent No. 608,676, dated August 9, 1898, and 45 is briefly described below, and afterward the improvements which are the subject of the present application for a patent are accurately detailed both as regards their construction and method of working.

The shaft *w'*, actuated by the driving-pulley *P*, imparts motion, by means of bevel-gears *k*² *k*, to a vertical shaft *w*. On the latter a boss *N* is fixed, and on this the electromagnets *E*, which drive the shuttles *s*, are fastened. These electromagnets receive the current from some source through the intermediary of an insulated friction-contact mounted upon the shaft *w*. It consists of a ring *m*⁵, made of some insulating material, (wood, hard rubber, ebonite, &c.,) upon which four brass rings *a* *a'* *a''* *a'''* are mounted. A brass spring *m*⁴ is in frictional contact with each of these brass rings, two of which are connected with the source of current by wires *m'* *m*² through the intermediary of the brush-holder *m*³. At 55 the other side conducting-wires *m*⁸ *m*⁹ lead from the rings to the magnets *E*. Over rollers *r*, which are fixed on the cross-pieces *T* of the frame, the toothed disk or rack *R* is rotated, being driven from the main shaft *w'* by 60 means of beveled wheels *k'* *k*³, the counter-shaft *w*², and the pinion *z*.

The warp intended to be used is carried to the harness-heddles *g* from the warp-beams over laths *c*, and the warp-threads *n* *n'* must 75 during their course first pass through cross-rings *h* *h'* in order to be properly arranged in a circle. The upper cross-ring *h* is encircled by a spiral spring, and into each spiral 80 the warp-threads pass.

The harness-heddles *g*, which have an eye in the center, have their bent ends carried in the grooves *x*⁵ *x*⁶ of eccentrics *x*² *x*³ in order to form the shed, while on the other side they are fixed radially between the reeds *b* of the 85 heddle-leaves *b* *b*². The heddle-leaves *b* *b*² are constructed in the same way as in the ordinary plain looms, except that they are circular in shape, and the reeds *b* are not parallel, but radial to the center.

To the under side of leaf *b*² a ring *f*, made of a diamagnetic material, is fixed, while a second ring *f'*, made also of diamagnetic material, has its boss *f*² loosely mounted upon the center shaft *w*, so that it does not revolve 95 with the shaft. Between these two rings *f* *f'* the ends of the magnets *E* move, on the poles of which brass caps *K* are fixed, which dur-

ing the rotation of the electromagnets push any loose-hanging inner warp-threads into their proper position. The magnets E act direct through the inner warp-threads vertically 5 on the paramagnetic rollers *sr* of the shuttles *s*, so that they are compelled to revolve with the rotation of the shaft *w* and roll along the rings *f'f*.

Owing to the vertical action of the magnets 10 E on the shuttle-rollers *sr* any displacement of the shuttles *s*, such as pressing against the warp-threads, is prevented, while owing to the direct and immediate action of the electromagnets E on the shuttles *s* the driving is 15 effected with a very small outlay for the current.

In order to press any warp-threads crossed in the shed into the level of the tightly-stretched warp, angle-shaped shoulders 20 25 *2c* are fixed on the shuttles *s*. The shuttles are prevented from sinking into the pointed part of the shed by the arms *a⁵* of the lever *bl²*, which projects underneath the shuttles into the shed, these arms forming a firm support 25 on which the shuttles can easily move on their pairs of rollers *sr²*. These lever-arms *a⁵* at the same time serve to beat up the weft-picks to the cloth. Their salient characteristics and mode of operation have already been made 30 known in our former patent aforesaid. They are arranged in such a way that several reeds *a⁵* are joined to form a slay *a⁷*, which by means of the top *d* and a screw is fastened to the lever *bl²*. By this means a large number of levers *bl¹* *bl²* are saved as contrasted with the previous arrangement, while the levers are more easily adjusted and more accessible. In order to stop the rotary loom when a weft-thread breaks or slips out, a two-armed pivoted lever *a'* is fixed on the upper shuttle-guide ring *f* between two bearing-angles *a*. By means of a spring *a''* the pointed end of the lever *a'* which projects into the shed is pushed away, so that the contact-pin *d'*, joined 40 up to the other end of the lever *a'*, and which is covered with platinum underneath and carried into the top of the case *e*, is put out of contact with the contact-pin *d''*, which is screwed into the bottom of the case and coated 45 at the top with platinum. It should here be pointed out that the top and bottom of the case *e* are electrically insulated from each other.

In order to secure the contact on the breakage or failure of the thread, a spring *g²*, fitted 50 with an eye *g'* and an upward bend *g''*, is fixed on the shuttle *s* and carried through a slot in the shuttle-box. To render a stoppage possible, the weft-thread coming from the cops 55 or bobbins passes between the pin *i'* and the spring *i²*, adjoining the latter, then passes through the eye *g'* of the spring *g²* and is carried through the tube *k⁶* to the cloth. As long 60 as the weft-thread passes through the eye *g'* the spring *g²* is, owing to the arrangement above described, drawn away, and therefore 65 when the shuttle *s* rotates cannot come into

contact with the lever *a'*. When the weft-thread breaks or gets displaced, the spring *g²* in consequence of its elastic power lifts the bend *g''*, which, as soon as the shuttle passes underneath the lever *a'*, turns the latter, so that the contact-pins *d' d''* come into contact with each other and close the electric circuit. This current, the course of which will be described later, puts into play the arrangement for throwing the machine out of gear and a brake appliance combined with same. The former is effected when the current energizes a solenoid *sE*, which attracts into itself an iron core *hs'*, until it strikes an iron plug *sE'*, thus releasing the spring *Gf*, which moves the strap-fork *u*, by which means the belt is pushed from the fast pulley *P* to the loose pulley *L*. 75

On the arm of the strap-fork *u* there is a roller *v*, which serves as a lock or detent for a rock-arm *3*, which moves around the pin *1* of the bearing *2* and which roller revolves around the pin *v'*. On the free end of the lever *3* there is a pin *4*, which glides into a slot *5* of the two-armed lever *7*, pivoted on the pin *6*. The lever *7*, which on one side is under the influence of the spring *8*, on the other side is pivotally connected with an adjustable connecting-rod *9*. The lower end of this rod engages with the brake-lever *11*, pivoted on the pin *10*, which said lever carries at its free end the brake *12*, pivoted on a pin *13*. When the belt-fork is turned in the manner described, this brake is pressed onto the annular rack or toothed disk *R* of the loom as the roller *v*, when this turning of the strap-fork takes place, releases the lever *3*, whereby the spring *8* turns levers *3* and *7* and by means 95 of the rod *9* draws down the brake-lever *11*. 100

In the above-described throwing out of gear of the loom by the electric contact in the weft-guard the course of the current is as follows: From each of the conducting-wires *m' m²*, 110 which lead from the source of the current to the electromagnets E, conducting-wires *3'* and *4'* lead to one of the free extremities *1* of the wire of the solenoid-spool *sE*. The free extremity *2* of the second wire of said 115 spool *sE* is connected with the connected levers *a'* by means of the conducting-wire *5'*. The current flows as follows: Branching off from the main current it passes through the wire *4'*, through the solenoid-spool *sE*, and through the wire *5'* into one of the levers *a'* of the weft-guard, then through the contact-pin *d''* (which is brought in contact with the lever *a'* when the weft breaks) and through the wire *3'* back to the main conductor. 120

In order also to bring into play the arrangement for throwing out of gear and applying the brake above described to stop the loom if from any cause one of the magnets E should allow its shuttle *s* to escape, the following 130 shuttle-guard arrangement has been devised: Between the magnet-spoils E there is a cylinder *14*, in which a piston *15*, constantly pressed out by a spring *16*, is loosely fixed, 125

On one of the surfaces of this piston 15 and of the cylinder-top 20, facing each other, a contact-ring 21 is fixed. In the fork-shaped end of the rod 17 of the piston 15 a roller 18, which revolves easily, is inserted. When the shuttle is attracted by the magnet, this roller is pressed inward by the shoulder 19, fixed on the former, in such a way that the contact-rings 21 are separated. Of course the piston 15 and the cylinder-top 20 are electrically insulated from each other. As soon as a shuttle is released from its magnet the piston 15 is pressed by the spring 16 onto the cylinder-cover 20 and the circuit is closed, which serves to stop the loom in the same way as previously described.

The putting-in circuit of the electric connection is as follows: Both shuttle-guard pistons 15 are connected with each other and 20 with the contact-ring α^2 by the wire 6. The contact-spring m^4 , which rests upon said contact-ring α^2 , is connected with the main conductor m^2 . Both shuttle-guard covers 20 and the contact-rings 21, arranged upon the same, 25 are connected and communicate with the contact-rings α^3 by means of wire 8. The spring m^4 , which rests upon said rings, is connected with the extremity 2 of the wire of the solenoid-spool sE through the intermediary of its 30 brush-holder and of the wire 9.

In the just-described circuit when one of the shuttles releases its magnet, bringing thereby rings 21 or the cover 20 in contact with the piston 15 of a shuttle-guard, the current flows as follows: Starting from the main conductor m' , it passes through the wire 4, through the solenoid-spool sE , into the brush m^4 and the contact-ring α^3 , then through the wire 8 into the shuttle-guard cover 20, respectively, their contact-rings 21, then through the wire 6 to the contact-ring α^2 , and thence through the brush m^4 , its holder m^3 , and the wire 7 to the main conductor m^2 . It should here be pointed out that the contact-rings 45 may be omitted, in which case the circuit would be closed by the direct contact of the piston 15 and the cylinder-top 20. As the cloth runs off the templet-ring C it is carried over a shaper-guide 22, fixed on the latter, 50 which shaper has the same horizontal circumference throughout, being circular at the top and wedge-shaped underneath for the purpose of unfolding the tubular-shaped cloth from its circular shape as it comes from the 55 loom and guiding same to the delivery-rollers, which are driven from the main shaft w' by means of chain 23 and interchangeable toothed wheels 24.

We claim as our invention—

60 1. In a circular loom, the combination with electromagnets rotatably mounted on an upright shaft, of one or more shuttles having upright rollers each lying in the same radial line with a magnetic pole, and transverse rollers to maintain the shuttle in the plane of the magnets, substantially as described.

65 2. In a circular loom, the combination with

electromagnets rotatably mounted on an upright shaft, of stationary parallel rings between and within the plane of which the pole-pieces of said magnets move, and one or more shuttles having upright rollers resting against said rings in the same radial line with the pole-pieces, substantially as described. 70

3. In a circular loom, the combination with 75 electromagnets rotatably mounted on an upright shaft, of stationary parallel rings between which the pole-pieces of said electromagnets move, one of said rings being grooved, weft-beating reeds adapted to enter and rest 80 in said groove, and one or more shuttles having upright rollers to run on said rings opposite the pole-pieces, and transverse rollers supported on the reeds, substantially as described. 85

4. In a circular loom, the combination with the electromagnetic shuttle-driving gear, of beveled caps on the pole-pieces of the electromagnets, for the purpose of returning loosely-hanging warp-threads to their proper plane, 90 substantially as described.

5. In a loom, the combination with an electric stop-motion, of one or more levers projecting into the shed and movable in planes parallel with the warp-threads, a circuit-closer controlled by said lever, and a shuttle carrying a lever-tripping device normally held out of action by the weft-thread, substantially 95 as described.

6. In a circular loom, the combination with 100 an electric stop-motion, of one or more levers projecting into the shed, a contact on the lever, a casing inclosing the end of said contact and the other terminal of the circuit, and a shuttle-carrying means for moving the lever 105 when the weft-thread breaks, substantially as described.

7. In a circular loom, the combination with 110 an electric stop-motion, of one or more levers projecting into the shed and movable in planes parallel with the warp-threads, a circuit-closer controlled by said lever, and a shuttle carrying a spring normally held down by the weft-thread but adapted to rise and trip the lever when the thread breaks, substantially as described. 115

8. In a loom, the combination with a belt-shifter, of a spring for actuating it, and a detent for said spring, consisting of a solenoid, a stationary core in one end thereof, a movable core in the other end, a spring to throw the movable core into the path of the shifter-actuating spring, and a stop-motion electrically connected with said solenoid, substantially as described. 125

9. In a circular loom, the combination with the belt-shifter u , having a roller v , of a rock-arm 3 resting on said roller, a lever 7 connected therewith, a spring 8 for actuating said lever, a brake-lever 11, an adjustable rod 130 9 connecting the levers 7 and 11, a brake-shoe 12 on the lever 11, and an annular rack R engaged by the brake-shoe, substantially as described.

10. In a circular loom, the combination with an electromagnetic shuttle-driving gear, of an electric stop-motion, a circuit-closer therefor carried by the driving-gear, and a shuttle provided with means for keeping said circuit-closer normally open, substantially as described.
11. In a circular loom, the combination with an electromagnetic shuttle-driving gear, of an electric stop-motion, a circuit-closer therefor carried by the driving-gear and comprising a spring-actuated contact, and a shuttle having a projection adapted to engage with said contact, substantially as described.
- 15 12. In a circular loom, the combination with electromagnetic shuttle-driving gear, of a casing, a spring-actuated piston therein, a circuit-closing contact on said piston, a piston-rod projecting from the casing, and a shuttle

carrying a projection which engages with the end of the piston-rod, substantially as described.

13. In a circular loom, the templet-ring C having a uniform circumferential measurement on planes perpendicular to its axis being circular at the top and wedge-shaped at the bottom, in order to properly fold the finished goods and feed the same to the delivery-rollers, substantially as described.

In testimony that we claim the foregoing as our invention we have signed our names in the presence of two subscribing witnesses.
